CLEANING DEVICE

Hester W. Hunter, Geneva, Ill.

Application April 17, 1933, Serial No. 666,419

6 Claims. (Cl. 15—228)

My invention relates to an improvement in mops or cleaning devices and has for one purpose the provision of a mop or cleaner which shall be simple in operation, and convenient in use. Another object is the provision of a mop with which may be employed a refill element or elements for use, whereby the cleaning element of the mop may readily be renewed. Another object is the provision of a removable or refill 5 element for such a mop. Other objects will appear from time to time in the course of the specification and claims.

I illustrate my invention more or less diagrammatically in the accompanying drawing, 15 wherein—

Figure 1 is a front elevation;

Figure 2 is a side elevation of the lower portion of Figure 1;

Figure 3 is a section on the line 3—3 of 20 Figure 1;

Figure 4 is a section on the line 4—4 of Figure 1;

Figure 5 is a detail illustrating the refill; and

Figure 6 is a detail illustrating a slight variation of the device.

Like parts are indicated by like symbols throughout the specification and drawing.

Referring to the drawing, A generally indicates any suitable handle which may removably 30 penetrate a socket B. The socket B is herein shown as terminating in a flattened stem B¹ with a jaw end member B² at the end thereof. Opposed to it is a second corresponding jaw member B³ the two being removably connected 35 as by the screw B⁴ and thumb nut B⁵. The jaw members are provided with opposed concavities B⁶ each of which may be penetrated by one or more positioning or securing lugs B⁷.

C generally indicates the cleaning member 40 proper which includes a central staff or stem C¹ which may be of cardboard, fiber or the like, or any other suitable material. It may be apertured as at C² to conform to the lugs B⁷. Each end of the member C¹ is provided with a roll of 45 a suitable cleansing material C³ which may be of paper, fiber or any other suitable substance preferably a substance which may be readily torn such as paper. The rolls C³ are separated by an intervening space C⁴ adapted to permit 50 the entry of the jaw members B² B³ and their proper engagement of the member C¹.

D is a transverse securing member herein indicated as a relatively thin sheet or blade of metal. Preferably the ends terminate well within 55 in the ends of the rolls C³. The member D may be placed unitarily against both the rolls C³ as by the spring D¹ which may be compressed between the member D and the abutment D² on the socket B. The member D may be guided on 60 a stem D³ which also passes through the lug D²

and is provided with a manual handle D⁴ whereby the member D may be upwardly withdrawn away from the rolls C³.

It will be noted that the material of which the roll C³ is formed reduces in width toward the interior of the roll, so that the surface of the roll which is in use always serves to protect the edge of that portion of the roll which is inside.

E indicates any suitable container for any oil or liquid medium which may be applied to the roll C³. I illustrate the container as removably mounted on a clip E¹ which in turn is secured to the socket B. It will be understood that any suitable oil container may be employed and I illustrate a container which may be manually removed by the operator for manual use. It will be understood, however, that a more or less fixed container may be used with any suitable duct or extension whereby oil from the container may be delivered directly to the roll C³ without manual intervention.

It will be realized that whereas I have described and shown a practical and operative device, nevertheless many changes might be made in the size, shape, number and disposition of parts without departing from the spirit of my invention. I therefore wish my description and drawing to be taken as in a broad sense illustrative and diagrammatic rather than as limiting me to my specific showing.

The use and operation of my invention are as follows:

I find it desirable, in cleaning walls, floors, furniture and the like, to provide a mop which may be employed with a renewable cleaning element, whereby after the cleaning element is exhausted it may be thrown away and a new one added. I therefore provide a plurality of rolls C³ of paper, fiber or the like or any other suitable material, which rolls are mounted, preferably with a slight intervening space C⁴, upon a single member C¹. The two rolls and the stem therefore form a unitary refill which may be readily stored in bulk or shipped and which may be individually applied to the jaws B² B³ when the device is put into use or after previously used members have been used up and thrown away. The lugs B⁷ penetrate the aperture C² in the member C¹, preventing rotation or endwise movement of the member C¹ when the jaw elements B² B³ are in the locked position in which they are shown in Figure 3. It may be of advantage to have lugs of a particular and somewhat unusual pattern or to have the jaws shaped otherwise than circular, so that the manufacturer of the mop may control the quality and type of the refills sold for use therewith and prevent the employment with this mop of inferior refills. Since the member D terminates well within the ends

110
115
120

of the rolls C^3 the rolls have soft ends which may abut against and engage furniture, walls, floors and the like without marring or scratching. As above pointed out any suitable oil or 5 cleaning medium may be applied.

In use the member D holds the end of the paper or material of each roll C^3 fixed against escape and also is sufficiently powerfully thrust by the spring D^3 to lock the roll as a whole 10 against rotation about the stem C^1 . If desired, the roll C^3 may be otherwise readily rotatable about the member C^1 in such fashion that the user by relieving the member D or drawing it up away from the roll may then pull out the 15 loose end of the roll and tear off the dirty previously exposed portion and expose a new clean portion. It is possible, although probably less convenient, in case the rolls C^3 are fixed against rotation in relation to the stem C^1 , to release 20 the jaws B^2 and B^3 and rotate the refill as a whole.

For purposes of shipment the members A and B may be made separable, for example formed with engaging screwthreads.

25 The container E may be employed for any desired oil or the like which may be applied to the mop or roll C^3 .

In the use of the device it may be understood that different types of material may be used for 30 different purposes, or that different lengths of roll C^3 and member C^1 may be desired for different purposes. The manufacturer may therefore ship each mop element with a plurality of 35 refills of different character or fiber or material or of different length, all being equally readily usable with the device and being readily removable therefrom.

It will be understood that the device may be used as a hand mop by simply detaching the 40 handle A from the socket B . Any suitable connection may be employed, including for example screwthreading of the opposed members.

Whereas I have described the oil container E as attached to the clip B^1 it will be understood 45 that a corresponding container may be inserted within the roll C^1 as shown for example in Figure 1.

For some purposes it may be preferable to employ, instead of the single transverse pressure 50 member D a plurality of individual members, one for each roll. Therefore in Figure 6 I illustrate a variant form in which the lug D^2 is laterally extended to form a transverse member G there being two separate members G^1 to direct pressure against the rolls C^3 each such member G^1 having a separate guiding stem G^2 with its handle G^3 and spring G^4 .

I claim:

1. In combination, a handle, securing means 60 at one end of said handle, and a mop element adapted to be held by said securing means, said element including a removable stem and a plurality of rolls of cleaning material surrounding said stem, said rolls being closely adjacent on 65 said stem and being positioned one on each side of said securing means, said securing means including jaw elements adapted to engage said stem, at a point between said rolls, said jaw elements being provided with penetrating members, said stem being formed to conform to said 70 penetrating members and to permit their penetration.

2. In combination, a handle, a rotatable cross piece on said handle, a plurality of individually removable cleaning members mounted on said cross piece, each of the cleaning members including a roll of cleaning material, yielding means mounted on said handle, effective normally to prevent movement of said cleaning members, said yielding means including an actuating spring, and a transverse blade adapted for simultaneous operative contact with both cleaning members, and guiding means on said handle for guiding the movement of said blade toward and away from the roll, and an additional manual handle, associated with said blade and operable for its manual withdrawal along said guiding means and against said spring. 80

3. In combination, a support, a roll of cleaning material removably mounted on said support, a handle for said support, a thrust member mounted on said handle and guiding means for said thrust member, effective to guide it toward and away from the roll, said guiding means being mounted on said handle, and yielding means effective normally to urge said thrust member against said roll of cleaning material and into holding contact therewith at a point removed from the normal engagement of the outer surface of said roll with the surface to be cleaned. 95

4. In combination, a support, a roll of cleaning material removably mounted on said support a handle for said support, a thrust member mounted on said handle and guiding means for said thrust member, effective to guide it toward and away from the roll, said guiding means being mounted on said handle, and yielding means effective normally to urge said thrust member against said roll of cleaning material and into holding contact therewith at a point removed from the normal engagement of the outer surface of said roll with the surface to be cleaned, 100 and a manually engageable withdrawing handle for said thrust member. 105

5. In combination, a support, a roll of cleaning material removably mounted on said support, a handle for said support, a thrust member mounted on said handle and guiding means for said thrust member, effective to guide it toward and away from the roll, said guiding means being mounted on said handle, and yielding means effective normally to urge said thrust member against said roll of cleaning material and into holding contact therewith at a point removed from the normal engagement of the outer surface of said roll with the surface to be cleaned, 110 and into holding contact therewith at a point removed from the normal engagement of the outer surface of said roll with the surface to be cleaned, 115 and a manually engageable withdrawing handle for said thrust member. 120

6. In combination, a support, a roll of cleaning material removably mounted on said support, a handle for said support, a thrust member mounted on said handle and guiding means for said thrust member, effective to guide it toward and away from the roll, said guiding means being mounted on said handle, and yielding means effective normally to urge said thrust member against said roll of cleaning material and into holding contact therewith at a point removed from the normal engagement of the outer surface of said roll with the surface to be cleaned, said roll extending outwardly beyond 125 the ends of the support. 130

7. In combination, a support, a roll of cleaning material removably mounted on said support, a handle for said support, a thrust member mounted on said handle and guiding means for said thrust member, effective to guide it toward and away from the roll, said guiding means being mounted on said handle, and yielding means effective normally to urge said thrust member against said roll of cleaning material and into holding contact therewith at a point removed from the normal engagement of the outer surface of said roll with the surface to be cleaned, said roll extending outwardly beyond the ends of the thrust member. 140

HESTER W. HUNTER. 145
